UNITED STATES PATENT OFFICE.

EARL H. SHERBONDY, OF DETROIT, MICHIGAN, ASSIGNOR TO SIDNEY D. WALDON,
OF DETROIT, MICHIGAN.

INTERNAL-COMBUSTION ENGINE.

Application filed June 11, 1920, Serial No. 388,239. Renewed July 21, 1924.

To all whom it may concern:

Be it known that I, EARL H. SHERBONDY, a citizen of the United States of America, residing at Detroit, in the county of Wayne 5 and State of Michigan, have invented certain new and useful Improvements in Internal-Combustion Engines, of which the following is a specification, reference being had therein to the accompanying drawings.

10 The invention relates to internal combustion engines and has more particular reference to the means employed for quickly heating the intake when the engine is started to assist in the vaporization of the 15 liquid fuel. A further feature of the invention is the peculiar construction of the intake manifold, and still further, the means employed for automatically controlling the heating means as hereinafter set forth.

20 In the drawings:

Figure 1 is a cross section through an engine, to which my improvement is applied;

25 Figure 2 is a longitudinal section through the intake manifold.

30 A is the engine block. B is the exhaust manifold arranged on one side of the block, and C is the intake manifold, which as shown is arranged on the opposite side of the block. D is a conduit extending from the exhaust manifold B to the intake manifold C, being connected to a jacket E surrounding the intake manifold.

35 In the present state of the art various constructions have been devised for heating the intake by a portion of the exhaust gases. It has been found undesirable to over heat the intake, and therefore the amount of the exhaust which is used is necessarily restricted. As a consequence, when 40 the engine is started, a certain amount of time is required for the transference of sufficient heat to the intake to secure the best running condition, as otherwise there would 45 be an over-heating when the engine is in full operation. With the present invention I have provided means for almost instantaneously heating the intake when the engine is started without danger of over-heating 50 after the engine is in full operation. This is effected primarily by the arrangement of a valve or damper F in the main exhaust, which when closed will force all of the exhaust gases through the conduit 55 D and into the jacket E. This valve or

damper may, if desired, be manually controlled; but preferably, it is automatically controlled and with the construction shown it is actuated by the suction of the intake manifold. Thus when the throttle G controlling the intake is in idling position, the relatively high vacuum in the intake above the throttle is used for operating a motor H for closing the damper F. This damper is, however, preferably unbalanced 60 so that an excess of pressure acting thereon will cause it to automatically open. Also where the throttle G is opened and the vacuum in the manifold thereby reduced, this will permit the opening of the valve or 65 damper F.

70 The construction of the manifold C and the jacket E surrounding the same is such as to produce the desired heating effect and at the same time provide for easily cleaning any carbon deposit from the exhaust gases. As shown in Figure 2, the manifold C is cast integral with the jacket E, which latter is in the form of a cylinder extending the entire length of the manifold and 75 open at its opposite ends. These open ends are, however, normally closed by separate caps I secured by suitable means, such as the central bolts J, engaging a threaded aperture in a lug K upon the end of the manifold C. The manifold C is of the substantially T-shaped form having the central stem portion L, which leads from the carburetor, and the oppositely laterally-extending 80 portions which terminate in elbow bends M leading into the cylinder block. The points at which there is a change in direction of the current are the points where it is most desirable to concentrate the heat 85 and this is accomplished with my construction; first, by connecting the conduit B at a point directly opposite the portion L of the intake; second, by arranging baffles or 90 divisions at N within the jacket E, these extending longitudinally at substantially diametrically opposite points and compelling the exhaust gases to travel to the opposite ends of the jacket; third, by terminating the baffles N so that the exhaust gases will 95 sweep around the elbow bends M, concentrating the heating effect thereon. The gases will then pass beneath the baffles N to the center, where they will escape through an outlet conduit O.

100 With the construction described, when the 110

engine is started, the damper F will be closed, and consequently, all of the exhaust gases are compelled to pass through the conduit D into the jacket E. Here they will first impinge against the portion of the intake C which is directly opposite the portion L thereof, leading from the carburetor. Thus, any of the liquid fuel which is thrown out from the air current against the surface of the manifold at this point, where the direction of the current changes, will come in contact with the heated surface and will be vaporized. Again, at the elbow-bends M, any of the liquid fuel thrown against the surface will be vaporized and will pass as vapor into the engine. The heat which will be transferred from the exhaust is sufficient to almost instantaneously heat the manifold; but as soon as the throttle is opened, the valve or damper F will also open, permitting the greater portion of the exhaust gases to escape through the regular exhaust conduit.

What I claim as my invention is:

1. In an internal combustion engine, the combination with an exhaust manifold, of an intake manifold comprising a central portion leading from the carburetor, oppositely extending branch portions in alignment with each other and transverse to said central portion, a jacket surrounding said branch portions only, the ends of said jacket being open, and caps for closing the ends of said jacket.

2. In an internal combustion engine, the combination with an exhaust manifold and an intake manifold having a stem portion and portions extending laterally therefrom, of a jacket enclosing the laterally extending portions only of said intake manifold, a conduit for conveying exhaust gases from the exhaust manifold to said jacket, said conduit being connected to said jacket at a point opposite to the stem portion of said intake manifold, means for controlling the passage of exhaust gases through said conduit, and an outlet in said jacket at a point remote from the point of connection of the said conduit with the jacket for said exhaust gases.

3. In an internal combustion engine, the combination with an exhaust manifold and an intake manifold having a stem portion and portions extending laterally therefrom,

of a jacket enclosing the laterally extending portions only of said intake manifold, a conduit for conveying exhaust gases from the exhaust manifold to said jacket, said conduit being connected to said jacket at a point opposite to the stem portion of said intake manifold, means for controlling the passage of exhaust gases through said conduit, and means within said jacket for directing the exhaust gases to the opposite ends of the laterally extending portions of said intake manifold, and an outlet in said jacket for said exhaust gases, said outlet being located substantially at the longitudinal center of said jacket, at a point remote from the point of connection of said conduit with the jacket.

4. In an internal combustion engine, the combination with an exhaust manifold and an intake manifold having a stem portion and portions extending laterally therefrom, of a jacket enclosing the laterally extending portions only of said intake manifold, a conduit for conveying exhaust gases from the exhaust manifold to said jacket, said conduit being connected to said jacket at a point opposite to the stem portion of said intake manifold, means for controlling the passage of exhaust gases through said conduit, baffles within said jacket for directing the exhaust gases to the opposite ends of the laterally extending portions of said intake manifold, said baffles terminating short of the ends of said laterally extending portions and permitting the exhaust gases to sweep around the ends of said laterally extending portions, and an outlet in said jacket for said exhaust gases positioned on the opposite side of the said baffles from that of the connection between the conduit and the jacket.

5. In an internal combustion engine, the combination with an exhaust manifold, of an intake manifold comprising a central portion leading from the carburetor, oppositely extending branch portions in alignment with each other and transverse to said central portion, a jacket surrounding said branch portion, the ends of said jacket being open, and removable caps for closing the said jacket ends.

In testimony whereof I affix my signature.

EARL H. SHERBONDY.
